Sarah Somervy of Hartford Conn.

Letter Patent No. 2362. Date July 17, 1866.

Design for Clock Base Dov.

The Schedule referred to in these Letters Patent and making part of the same,

Scall whom it may concern:

I declare that I, Sarah Somervy of the
City and County of Hartford, and State of Connecticut have invented
or produced a new and original Design for Clock Base Dov; and
I do hereby declare that the following is a full and exact description
of the same, reference being had to the letters marked upon the photo-
graphic illustrations.

In the accompanying photographs, will be shown a
New and Original Design for Clock Base Dov:

a, is the door proper

b, is a raised circular base.

c, is a half circular raised base.

d, are straight raised base sides.

e, is a straight raised base bottom.

f, is a flat raised centre piece.

g, are rosettes, all combined and arranged to produce

a plain, rich Design for a Clock Base Dov.

What I claim and desire to secure by Letters Patent is,
the Design for a Clock Base Dov substantially as above described & illustrated
